[57] **CLAIM**

The ornamental design for cabinet for a speaker or the like, substantially as shown and described.

DESCRIPTION

FIG. 1 is a front elevational view of a cabinet for a speaker or the like showing my new design;
FIG. 2 is a right side elevational view with the cord broken off for convenience of illustration;
FIG. 3 is a top plan view thereof;
FIG. 4 is a rear elevational view with the cord broken off to indicate indeterminate length; and
FIG. 5 is a bottom plan view with the cord broken off for convenience of illustration.

FIG. 1

FIG. 2

FIG. 3

FIG. 4

FIG. 5
